UNITED STATES PATENT OFFICE.

HAAKON A. MARTIN, OF DAYTON, OHIO, ASSIGNOR TO THE NATIONAL CASH REGISTER COMPANY, OF DAYTON, OHIO.

TICKET PRINTING AND ISSUING MACHINE.

1,338,238.

Specification of Letters Patent. Patented Apr. 27, 1920.

Application filed May 14, 1917. Serial No. 168,515.

To all whom it may concern:

Be it known that I, HAAKON A. MARTIN, a citizen of the United States, residing at Dayton, in the county of Montgomery and State of Ohio, have invented certain new and useful Improvements in Ticket Printing and Issuing Machines, of which I declare the following to be a full, clear, and exact description.

10. This invention relates to improvements in ticket issuing machines and has particular reference to machines of the kind constructed to print and issue a variable number of tickets at an operation of the machine.

One object of the invention is to provide a simple, compact machine for use in the ticket offices of theaters and other places where tickets are used.

20. Another object of the invention is to provide a machine which can be operated to issue an indefinite number of tickets, as distinguished from machines in the prior art which can be operated to issue a variable 25 number of tickets up to a certain number only. In other words, the improved machine is not limited by its construction to issuing any maximum number of tickets, but can, if occasion demands it, issue practically an unlimited number of tickets by continuous operation of the machine.

Another object of the invention is to provide improved mechanism for machines issuing tickets of two or more classes which 35 will permit rendering the ticket printing and feeding devices of one class effective and allow them to remain undisturbed in effective condition until the last ticket of a series is delivered.

40. Another object is to provide mechanism whereby a machine lock and circuit controlling devices for an electric motor may be controlled for continuous operation, but which is so arranged that the machine lock and circuit controlling devices may be rendered effective to break the motor circuit and stop the machine whenever the desired 45 number of tickets has been produced.

With these and incidental objects in view, 50 the invention consists in certain novel features of construction and combinations of

parts, the essential elements of which are set forth in appended claims, and a preferred form of embodiment of which is hereinafter described with reference to the drawings 55 which accompany and form part of the specification.

Of said drawings:

Figure 1 is a top plan view of the improved mechanism, with some of the parts 60 omitted and others broken away.

Fig. 2 shows the face of one of the tickets printed and issued by the machine.

Fig. 3 is a rear view of the improved mechanism.

Fig. 4 is a detail of one of the cams for operating one of the ticket numbering devices.

Fig. 5 is a right side view of one of the ticket keys and the mechanism for temporarily latching the key in depressed position.

Fig. 6 is a section taken on the line 6—6 of Fig. 3, looking in the direction of the arrows.

Fig. 7 is a section on the line 7—7 of Fig. 12 and shows particularly the devices for insuring correct operative relationship between some of the ticket printing and feeding devices and the rest of the mechanism.

Fig. 8 is a section on the line 8—8 of Fig. 3, looking in the direction of the arrows.

Fig. 9 shows one of the cams for rendering the associated ticket printing and feeding mechanism ineffective after the desired 85 number of tickets has been issued.

Fig. 10 shows devices for latching the shaft controlling the ticket printing and feeding mechanism in either of its two positions.

Fig. 11 is a section on the line 11—11 of Fig. 3, looking in the direction of the arrows.

Fig. 12 is a front view of devices for feeding tickets and printing on the faces thereof 95 matter such as shown in Fig. 2, and shows particularly the construction of the frame supporting said devices.

The machine in the drawings is arranged to issue tickets of two different classes but, 100 as will be apparent later, by adding additional sections the machine can be made to

issue tickets of substantially any desired number of classes. The tickets of each class are fed from a separate strip by independently operable feeding mechanisms. The 5 strips may, if desired, be of different colors so that any one interested can readily distinguish one kind of ticket from the other.

For each kind of tickets there is provided a key which is to be depressed when tickets 10 of that kind are wanted. Depressing a key unlocks the driving mechanism, starts the motor, if the machine is electrically operated, and connects the corresponding ticket printing and feeding mechanism to the driving 15 mechanism. If the finger is removed from the key immediately when the driving mechanism starts a single ticket will be delivered.

By holding the key depressed the motor 20 and driving mechanism will operate the connected ticket mechanism continuously until the desired number of tickets has been produced. Each time the machine starts to issue a ticket the key will be given an impulse which can be felt by the operator and these impulses are to be counted by the operator to keep track of the number of tickets. When the last impulse is felt the finger is removed from the key and as soon 25 as the machine finishes issuing the last ticket the circuit through the motor is broken and movement of the driving mechanism arrested.

The ticket printing and feeding mechanism rendered effective by depressing a key 30 remains effective until the very end of the operation to issue the last ticket. That is to say, a section of ticket printing and feeding mechanism having once been rendered effective is not disturbed in any way, regardless of the number of tickets issued, until the operation to issue the last ticket is completed. The circuit controlling devices also remain undisturbed after the circuit is 45 once closed until the desired amount of work has been accomplished and the key released.

The machine is provided with a casing 20 of any suitable material and construction in order to protect the mechanism. 50 Two frames 21 and 22 at the right and left sides respectively support most of the mechanism and are connected together by two cross frames 23 and 24 suitably constructed to give the necessary amount of rigidity. 55 These cross frames are also used to support certain parts of the mechanism, as herein-after pointed out in detail.

Driving mechanism.

60 The machine is arranged to be operated either by means of an operating handle 25 (Fig. 1) or by means of an electric motor. The motor used is of the type fully shown and described in United States Letters Pat-

ent 1,144,418 issued June 29, 1915, to Chas. F. Kettering and William A. Chryst. Said patent also shows the operating and circuit controlling connections employed between the motor and the driving mechanism. The motor is not shown herein and only enough 70 of the circuit controlling connections, designated generally by the numeral 27 (Fig. 3), are shown to indicate where the power is applied to the machine.

The operating and circuit controlling connections just mentioned cause the motor to rotate a small gear 28 (Figs. 3 and 8) fastened to a short shaft 29 journaled in the right machine frame 21. The gear 28 meshes with a gear 31 loose on a rod 32 and 80 meshing with a small idle pinion 33. The pinion 33 meshes with a gear 34 fastened to a shaft 35 and with an idle gear 36 loose on a rod 37. The gear 36 in turn meshes with a small idle pinion 38 meshing with a gear 39 fastened to a shaft 40. The construction is such that at each operation to issue a ticket the shafts 35 and 40 are each given a complete rotation or cycle of movement.

The operating handle 25 (Fig. 1) has a 90 one way driving connection (not shown) with a bevel gear 45 meshing with a bevel gear 46 rigid with a gear 47 (see also Fig. 8). The gear 47 meshes with a large transmission gear 48 which in turn meshes with 95 the gear 39, previously mentioned. The operating handle gearing just referred to is so proportioned that each turn of the handle 25 will cause the shafts 40 and 35 to make a complete rotation in the same direction as 100 if they were driven by the motor.

In the normal condition of the parts the circuit through the motor is kept open and the motor held disconnected from the operating mechanism by an arm 53 (Figs. 1 and 3) in the manner fully described in the Kettering and Chryst patent referred to above. The driving shaft 35 is also normally held against movement by a stop 54 (Fig. 11) resting against an arm 55 fastened 105 to the shaft. When a key is depressed the arm 53 and the stop 54 are swung to ineffective position and the motor will then drive the shafts 35 and 40 one or more complete rotations depending upon the number 110 of tickets to be issued.

The keyboard and connections for controlling the motor and machine lock.

As before stated, the present machine has 120 two sets of ticket printing and issuing devices with a key for each device. These keys, as shown in Fig. 1, bear the numerals 5 and 10 to indicate the value of the tickets issued under their control. Each key consists of an arm 61 (Figs. 1, 5 and 6) loosely mounted on a shaft 62. Each key arm 61 carries a pin 63 normally resting against the 125

end of a spring tensioned hook or latch 64. When a key is depressed the latch 64 engages the stud 63 to hold the key in depressed position. Immediately after the driving mechanism starts to move, the latch 64 will be disengaged and held disengaged during the first half of the operation. The mechanism that disengages the latch gives the key a slight impulse which will be noticeable to the operator if the finger remains on the key but the key is not moved all the way back to its undepressed position. If the finger has been removed from the key, springs referred to more specifically later on return the key to its original position before the mechanism holding the latch 64 disengaged releases the latch.

Rigid with each of the key arms 61 is a hub 66 (Fig. 1) to which is fastened an arm 67 engaging a lug 68 formed on a lever 69 (see also Fig. 6) loose on the shaft 62. Springs 72 and 73 tend at all times to hold the key arms 61 and levers 69 in the positions shown. It is apparent that when a key is depressed the associated lever 69 will be rocked clockwise (Fig. 6) on the shaft 62. The levers 69 serve to connect the corresponding sections of ticket printing and issuing mechanism to the driving mechanism. They also coöperate with devices controlling an operating relationship between the keys and with devices controlling the completion of an operation of a ticket printing and issuing mechanism after such an operation is once begun.

Depression of a key 61 also rocks the shaft 62 and this moves the stop 54 (Fig. 11) to ineffective position and permits the arm 53 (Figs. 1 and 3) to be swung away from the position shown to release the devices for establishing a driving connection between the motor and the driving mechanism and at the same time close the circuit through the motor. This rocking movement is imparted to the shaft 62 by engagement of the lower edges of the key arms 61 with shoulders 77 (Fig. 1) of arms 78 fastened to the shaft 62. The arrangement is such that depression of either key will rock the shaft to the same extent. The connections for releasing the motor controlling arm 53 will be described first.

Fastened to the right hand end of the shaft 62 is a spring tensioned arm 81 (Figs. 1 and 8). As shown in the latter figure, the end of the arm 81 normally rests against the forward end of a flange 82 extending laterally from an arm 83 fastened to a rock shaft 84. Rigid with the arm 83 is an arm 85 carrying a stud 86 engaging a slot in the upper end of a lever 87 pivoted at 88 to the side of a lever 89 loose on a sleeve 90 which is in turn journaled on the rod 32. The lever 89 is normally stationary. The

lever 87 is pivotally connected at 92 to a link 93, which link at its rear end is pivoted to an arm 94 fastened to a sleeve 95 (Fig. 3) loose on a rod 96. An arm 97 also fastened to the sleeve 95 is connected by a link 98 to the arm 53 which, as before explained, controls the circuit and operating connections for the motor. A spring 99 is constantly under tension and will, when released, swing the motor controlling arm 53 clockwise (Fig. 8) to permit the motor to start the machine.

The spring 99 is released as soon as the end of the arm 81 (Fig. 8) is carried up far enough by depression of a key to clear the flange 82 on the arm 83 fastened to the shaft 84. The spring then rocks the motor controlling arm 53 clockwise (Fig. 8) thereby, through the link 98 and link 93, rocking the small lever 87 clockwise on its pivot 88. This necessarily rocks the shaft 84 in a counter clockwise direction and carries the flange 82 under the rear end of the arm 81.

At the time the shaft 62 is rocked to raise the rear end of the arm 81 above the flange 82, the arm 69 associated with the operated key is also swung as previously described to carry its rear end upward. When the shaft 84 is rocked counter-clockwise by the spring 99 a flange 101 (Fig. 6) projecting laterally from an arm 102 fastened to the shaft 84 will be carried under a stud 103 fastened to the side of the arm 69 for the operated key. The arm 69 for said key will, therefore, be latched in elevated position until the rock shaft 84 is restored. The flange 101 for the unoperated key will at the same time be carried above the stud 103 for said unoperated key so as to prevent depressing the second key after the other has been depressed to release the machine. The construction is such that both of the keys 61 may be operated simultaneously if desired so as to prepare and deliver tickets from both sections of the machine, but the depression of the keys must be simultaneous as one cannot be depressed after the machine has been started by depressing the other.

When more than one ticket is desired the pressure of the finger on the key 61 is maintained until the machine has started to deliver the last ticket. This pressure on the key 61 holds the controlling arm 81 (Fig. 8) up out of the path of the flange 82. As each ticket is issued the lever 89 is rocked first counter-clockwise (Fig. 8) and then clockwise about the rod 32 by a cam 111 (Fig. 9) coöperating with a roller 112 carried by the lever. The link 93 will at this time be stationary and the lever 87 (Fig. 8) will simply rock around its pivotal connection 92 with the link 93 thereby causing the lever 87 to rock the shaft 84 clockwise (Fig. 8) far enough to permit the arm 81 to drop

down in front of the flange 82 if the finger has been removed from the key 61. If the arm 81 has dropped into the path of the flange 82 then as the cam 111 rocks the lever 89 back to its normal position the upper end of the lever 87 will be held stationary and the lever 87 will be rocked counter-clockwise about the pin 86. This will draw the link 93 forward and operate through the link 98 to return the motor controlling arm 53 to the position where it will disconnect the motor.

As previously stated, the stop 54 (Fig. 11) normally co-operates with an arm 55 to prevent rotation of the driving shaft 35. When a key is depressed and the shaft 62 rocked, the stop 54 is swung out of the path of the arm 55 and the shaft freed for rotation. This swinging movement is imparted to the stop 54 by a link 113 connecting an arm formed on the stop and an arm 114 fastened to the rock shaft 62. It is apparent that as long as the shaft 62 is held in rocked position by pressure on a key 61 the stop 54 will be held out of the path of the arm 55 so that the stop will not interfere with rotations of the shaft 35. When the finger is removed from the key and the shaft 62 later rocked back to its normal position the stop 54 will be swung back to the position where it will intercept the arm 55 and positively stop the shaft 35.

As previously stated the depressed key 61 is temporarily locked in depressed position by the spring operated hook 64 (Figs. 5 and 6). At the beginning of each rotation of the driving shafts, these hooks are moved to ineffective position and are held in ineffective position to permit the operated key to return to its normal position if the finger has been removed. As an incident to moving the hook 64 to ineffective position the key is given an impulse which can be felt if the operator's finger remains on the key, thereby giving the key a pulsating movement which enables the operator to keep count of the operations and consequently the number of tickets issued.

The mechanism for releasing the key and giving the pulsating movement referred to, includes a short arm 115 (Fig. 11) fastened to the left hand end of a rock shaft 116. The key latching hooks 64 are pivoted on this shaft. Fastened to the shaft 116 are two arms 117 (Figs. 5 and 6) carrying pins 118 which, as shown in Fig. 1, extend under the lower edges of the keys 61 and under shoulders 119 rigid with the key latching hooks 64. The arm 115 (Fig. 11) is pivoted to the upper end of a pitman 121 having the usual roller 122 engaging a cam groove 123 in a disk 124 fastened to the driving shaft 40. As soon as the shaft 40 begins to turn the pitman 121 is drawn down and

the arms 117 (Figs. 5 and 6) swung up, 65 first to engage the shoulders 119 and unlatch the keys and then against the lower edge of the key which is held down and lift the key slightly. At the beginning of the latter half of the rotation of the shaft 40 the shaft 116 is rocked back to its original position and as the arm 117 moves away from the key finger pressure on the key will restore the key to its lowermost or fully depressed position. 75

Ticket printing and issuing mechanism.

The ticket printing and issuing mechanism comprises three plates 125 (Figs. 3, 6 and 12) fastened to a shaft 126 journaled 80 in the side frames 21 and 22. The three plates 125 are also connected by a shaft 127 journaled in the plates. Fastened to the ends of the shaft 127 are levers 128 provided with notches or hooks to engage studs 85 129 attached to the machine frames 21 and 22. The left hand one of the levers is provided with a handle 130 to permit rocking the shaft 127 to disengage the levers from the studs 129. The plates 125 may then be 90 swung forward to render conveniently accessible devices supported by the plates and hereinafter described in detail.

Fastened in the plates 125 is a rod 131 on which the loosely mounted eccentrics 95 132 forming bearings for impression rollers 133. Above the impression rollers 133 are two feeding and printing cylinders 134 and at the upper end of the plates 125 is a pair of ticket feeding and printing cylinders 136 100 with their outer trunnions 135 rotatably mounted in the outside plates 125. In order that the two cylinders 136 may rotate as a unit the inner trunnion of one has a rib 137 (Fig. 12) across its end co-operating 105 with a slot across the end of the trunnion of the next adjacent cylinder so as to form a clutch. The cylinders 134 are clutched together in the same way.

The right hand trunnion for the upper 110 pair of cylinders is provided with a gear 141 (Figs. 7 and 12) normally engaging a gear 142 fastened to the sleeve 90 previously described as being loose on the rod 32 and rigid with the gear 31 (Fig. 8). As previously indicated, the gear 31 makes a complete rotation at each ticket issuing operation and the intermediate gearing is so proportioned that the pair of cylinders 136 will also be given a complete rotation at each of 120 such operations.

Meshing with the gear 141 is a small intermediate pinion 145 (Fig. 7) which in turn meshes with a gear 146 fastened to the right hand trunnion 135 of the right hand cylinder 134, thereby causing the cylinder 134 to rotate in the same direction and the same distance as the cylinders 136. The cyl-

inders 134 and 136 are provided respectively with flanges 151 and 152 to coöperate with feeding rollers 153 and 154 to feed tickets.

Mounted in the cylinders 134 and 136 are consecutive numbering type wheels 157 (Fig. 12) and type wheels 158 for printing dates. Attached to the peripheries of the cylinders are type plates 159 for printing on the faces of the tickets invariable matter such as shown in Fig. 2 and one cylinder of each vertical pair carries a perforating blade (not shown) to perforate a line 160 between the body and coupon portions of the tickets.

15 The backs of the tickets are printed from type plates 171 (Fig. 6) attached to the peripheries of cylinders 172 fastened to the driving shaft 40. The matter printed by the type plates 171 is not shown in the drawings 20 but may be of any nature desired.

The impression rollers 153 and 154 coöperating respectively with the printing cylinders 134 and 136 are rotatably mounted on eccentrics 174 (Fig. 6) formed on sleeves 25 175 loose on the rods 32 and 37. Surrounding the sleeves 175 are members 181 (see also Fig. 3) rigid with clamps 182 gripping the sleeves. The clamps 182 are, as is well known in the art, provided to permit adjusting the eccentrics 174 to different positions according to the impression desired and then tightening the clamps to hold the eccentrics in adjusted position. Pivoted on the shaft 40 is a member 184 slotted to engage 30 a stud 185 carried by an arm 186 of a member carrying a clamp 187 holding in adjustment a sleeve 188 rigid with the eccentric 132 supporting the impression roller 133.

40 The members 181 for the impression rollers 153 and 154 and the member 184 operatively connected with the eccentric bearing member for the impression roll 133 are all provided with extensions pivoted to a link 191. An arm 192 rigid with the upper member 181 is pivoted to the lower end of a member 193 provided with a slot 194 surrounding a stud 195 projecting from the side of the arm 69. The member 193 also 45 carries a stud 196. When a key is depressed and the corresponding arm 69 rocked upward the stud 195 and slot 194 will coöperate to swing the member 193 upward to engage the stud 196 with a slot 197 in an 50 arm 198 fastened to a rock shaft 199. At the beginning of the movement of the driving shaft 35 the shaft 199 is rocked clockwise (Fig. 6), thereby causing a flange 200 (Figs. 1 and 6) extending laterally from an 55 arm 201 fastened to the shaft 199 to pass under a stud 202 on the arm 69 and also causing the arm 198 to thrust the member 193 downward. This downward movement of the member 193 rocks the member 181 counter-clockwise (Fig. 6), thereby causing

the eccentric 175 to swing the impression roller 154 into printing relation with the cylinder 136. This movement is transmitted by the link 191 to the eccentric 174 for the impression roller 153 and, through the member 184, is transmitted to the eccentric 132 for the impression roller 133 coöperating with the cylinder 172 for printing the backs of the tickets. The mechanism for rocking the shaft 199 will be described in detail 70 later, it being sufficient at this point to state that when the shaft is first rocked to carry the flange 200 under the stud 202 and swing the impression rollers into printing relation with their ticket printing elements a condition is established which remains until at the very end of the operation to issue the last ticket. At that time the flange 200 is withdrawn from engagement with the stud 202 and the spring 73 will then return the 80 arm 69 to the position shown and disengage the stud 196 from the slot 197 in the arm 198.

The shaft 199 is rocked to rotate the eccentrics 174 and 132 (Fig. 6) to carry the impression rollers into engagement shortly 90 after the driving shaft 35 begins to turn to issue the first ticket. The shaft 199 then remains in rocked position until just at the end of the rotation of the driving shaft 35 to issue the last ticket of a series.

95 The mechanism for so rocking the shaft 199 is best shown in Fig. 8. It comprises a link 211 having a slot surrounding a stud 212 attached to an arm 213 fastened to the shaft 199. The lower end of the link 211 is pivotally connected to a bell crank 214 loose on the rod 96. The other arm of the bell crank 214 is pivoted to the upper end of a pitman 215 actuated by a cam groove 216 in a disk 217 (see also Fig. 3) fastened to 100 the driving shaft 35. The cam groove 216 is so shaped that shortly after the shaft 35 begins to turn the pitman 215 is thrust upward, thereby drawing the link 211 downward and rocking the shaft 199 in a clockwise direction. This, as will be seen by referring to Fig. 6, will carry the flange 200 under the stud 202 attached to the side of the lever 69 associated with the depressed key. It is clear that the flange 200 will hold the 110 arm 69 in elevated position and the printer connecting member 193 engaged with the operating arm 198 until the shaft 199 has fully completed its movement back to its normal 115 position.

120 Whether the shaft 199 returns to its original position at the end of the first rotation of the shaft or at the end of some subsequent rotation depends upon the position of a connecting member 221 (Figs. 1 and 8). Said connecting member is pivoted on the stud 212 and comprises two arms, one of which is provided with a slot 222 surrounding a stud 223 attached to the forward end of the link 93 previously mentioned. The other arm of 130

the connecting member 221 is normally in engagement with a square stud 225 attached to the side of the link 211. When the motor controlling arm 53 is released and rocked 5 clockwise (Fig. 8) by its spring 99 and the link 93 drawn rearward the link 93 will rock the connecting member 221 clockwise slightly on its pivot 212 so as to carry the one arm of the member out of the path of 10 the stud 225 on the link 211. If the motor controlling arm 53 is returned to its normal position during the first rotation of the driving shaft 35 its return will be completed in time to swing the connecting member 221 15 back toward its original position before the pitman 215 is drawn back down to its normal position and the link 211 thrust upward. The stud 225 will then coöperate with the associated arm of the connecting member 20 221 to rock the shaft 199 back to its normal position.

If, however, the finger pressure on the key 61 is maintained throughout the operation and the motor controlling arm 53 consequently 25 prevented from assuming its normal position the link 93 will hold the connecting member 221 in its rocked position, that is with its short arm out of the path of the stud 225. Then when the link 211 is given its upward thrust by the pitman 215 the shaft 199 30 will not be disturbed. As soon as the finger is removed from the key, however, and the arm 81 (Fig. 8) allowed to drop down into position to oppose the flange 82 and thereby 35 cause the motor controlling arm 53 to be returned to its normal position the connecting member 221 will be moved back into position for its short arm to intercept the stud 225 as the link 211 makes its final movement 40 with the result that the shaft 199 will be rocked back to its first or normal position and the impression roll eccentrics swung in the proper direction to move their rolls out of feeding relation with their printing and 45 feeding cylinders.

The shaft 199 is held in either of its two positions by a spring operated lever 231 (Figs. 1 and 10) pivoted on the end of the shaft 62. The rear end of the lever is suitably 50 formed to engage with notches in a member 232 fastened to the rock shaft 199. It is clear that the lever 231 and member 232 will coöperate not only to adjust the shaft slightly if necessary to insure correct position of the shaft 199 but will also serve to hold the shaft against accidental displacement during operation of the machine.

The consecutive numbering type wheels 157 (Fig. 12) are constructed to operate on 55 the well known deep notch principle. None of the mechanism directly engaging the number type wheels to actuate them is shown in the drawings. This mechanism is however operatively connected to a small rock plate 235 (Fig. 4) loose on a shaft 236. At

the opposite ends of the plate 235 are rollers 237 projecting through slots 238 in the ends of the cylinders and into the planes of cam arms 239 rigid with the eccentric operating members 181. In the normal position of the 70 parts the cam arms 239 are down in the position shown in Fig. 6 but if the eccentric operating members 181 are actuated to swing their impression rollers into printing position the cam arms 239 will be carried to the 75 position shown in Fig. 4. In the latter position a cam edge 240 of each arm will be in such a position that, as a printing cylinder is rotated, first one stud 237 will engage the cam edge 240 and then the other stud 237, 80 with the result that the plate 235 will be oscillated first clockwise (Fig. 4) and then counter-clockwise. This oscillation of the plate serves through the operation mechanism (not shown but referred to above) to 85 add one to the amount previously shown on the consecutive number type carriers 157. It is clear, of course, that as the eccentric members may be set and retained in set position so as to hold their impression rolls 90 stationary in feeding position until the last ticket of a series is issued the cam arms 239 will also be held stationary in position to act upon the consecutive number operating studs 237 until after the last ticket of the series 95 has been delivered.

The consecutive numbering devices in the cylinders may be turned to zero at any time desired by manually operating knurled disks 251 (Fig. 12) rotatable on the right hand 100 trunnions 135 of the cylinders. Rigid with the knurled disks 251 are members 252 having internal teeth (not shown) for turning the consecutive number type carriers 157 to zero. The details of this resetting mechanism are not shown in the drawings, because they are not an essential part of the present invention.

For the sake of clearness, no inking rollers are shown in the drawings. However, the 110 ink rollers for the cylinders 134 and 136 are mounted in extensions 255 (Fig. 3) on the front edge of the plates 125. This location of the ink rollers would, if no means were provided to offset it, make it extremely difficult 115 to get at the cylinders 134 and 136. This is the reason for the pivoted frame comprising the plates 125. When it is desired to have access to the cylinders mentioned a door 261 (Fig. 6) in the front of 120 the casing is swung downward on its hinges 232 and the handle 130 may then be operated to disengage the levers 128 from the studs 129. The plates 125 and their contents may then be swung forward on the pivot 126 125 until the plates are in a nearly horizontal position. The consecutive numbering devices may then be turned to zero by manipulating the knurled disks 251 (Fig. 12) and the date printing type carriers 158 may also 130

be manually adjusted to set up the correct date. Before the date type carriers 158 are readily accessible, however, the cylinders 134 and 136 must be turned about one-third of a revolution. This is done by manually operating a knurled knob 263 (Fig. 12) rigid with the right hand trunnion of the right hand cylinder 134. After the consecutive numbering device has been turned to zero and the date type carriers set the knob 263 is then turned in a reverse direction to bring an arrow 266 (Fig. 7) stamped on the gear 141 in alignment with an arrow 267 stamped on the adjacent plate 125. When these arrows are in alignment a shoulder 271 on a disk 272 rigid with the gear 141 is in position to enter a notch 273 in the periphery of a disk 274 (see also Fig. 3) rigid with the gear 142 previously mentioned. The arrows 266 and 267 and the shoulder 271 and notch 273 all coöperate to insure establishing correct relationship between the cylinders 134 and 136 and the operating mechanism when the plates 125 are swung back to their inner position.

Knife operating mechanism.

Fastened to a support 275 (Figs. 3 and 6) is a stationary knife 276 and for each of the ticket strips there is provided a movable knife 277. The stationary knife has slots 278 through which the ticket strips pass and the movable knives have recesses engaged by studs 279 on the lower faces of plates 280 each forming part of a yoke, the side arms 281 of which are pivoted on rods 282. Each rod 282 is supported at one end in a plate 283 and at the other by an arm 284, the plate 283 and arm 284 being rigid together on a sleeve 285 loose on a shaft 290. A spring 286 acts against the cross plate 280 of the knife yoke in such a way as to hold the movable knife 277 in sliding engagement with the upper face of the stationary knife 276.

When a set of eccentrics is rotated to carry the impression rollers for a strip into feeding position the movable knife 277 for that strip is operatively connected to the driving mechanism. For this purpose the lower end of each link 191 (Fig. 6) is pivotally connected to a link 291 carrying a stud 292 extending through a straight slot in the forward end of a lever 293 loose on a rock shaft 294 and into a bayonet slot 295 in an arm 296 fastened to the rock shaft 294.

Fastened to the shaft 294 is an arm 302 carrying a roller 303 coöoperating with a cam groove 304 in the side of a disk 305 (see also Fig. 3) fastened to the driving shaft 35. The shape of the cam groove 304 is such that shortly after the driving shaft begins to turn the shaft 294 will be rocked clockwise (Fig. 6) and held in rocked posi-

tion until the end of the rotation of the driving shaft when it will be rocked counter-clockwise to its original position. In the normal position of the parts the studs 292 are in position to coöperate with a portion 307 of the bayonet slot 295 in the arm 70 296 and the levers 293 will not be moved. When a link 191 is thrust downward, however, to rotate the impression roll eccentrics, the corresponding link 291 will be drawn forward so that its stud will coöperate with the forward portions of the slots in the lever 293 and arm 296. The forward portions of the slots are the same in width and the stud 292 will, therefore, form a bond between said arm and lever so that the rocking movement of the shaft 294 will be imparted to the lever. As a result of the movement of the lever 293 the link 301 will be thrust upward and the connected movable knife 277 drawn rearward to clear the slot 85 278 in the stationary knife 276 so that the ticket strip may be fed through the slot. When the shaft 294 is rocked back to its original position the movement of the knife operating parts is reversed so that the movable knife is slid back to the position shown and as it moves back it coöperates with the stationary knife to sever the strip. The bond or operating connection established by the stud 292 will, of course, remain effective 95 until the impression roll eccentrics are rotated back to their normal position after the last ticket of a series has been issued.

Ticket delivering devices.

After being severed from the strips the tickets are fed out of the machine by knurled disks 311 (Figs. 1 and 3) rigid together on sleeves 312 loose on a shaft 313. Coöoperating with the disks 311 are other 105 knurled disks 314 rigid with sleeves 315 rotatably supported as hereinafter described by a rod 316 (see also Fig. 6) supported at its ends in lugs 317 extending rearward from the cross bar 24 of the machine frame 110 work. Rigid with each pair of rollers 311 is a gear 321 and fastened to the shaft 313 adjacent each gear 321 is a gear 322. Associated with each pair of gears 321 and 322 is a clutch pinion 323 pivoted to the side of 115 one arm 324 of a three armed member loosely mounted on the rod 290. A downwardly extending arm 325 of each three armed member is provided with a laterally extending shoulder 326 engaging a cut-away portion 120 327 of the plate 283. The third arm 328 of the three armed member is formed laterally to bring it into the plane of the gear 321 and is suitably formed to engage the teeth of the gear.

When the knife operating link 301 is coupled to the operating mechanism as previously described and the link given its up-

ward thrust to draw the movable knife 277 rearward, the final movement of the plate 283 will swing the clutch pinion 323 into engagement with its companion gears 321 and 322, thereby connecting the feeding disks to the shaft 313.

The shaft 313 makes practically a complete rotation at each turn of the driving shaft 35. The gearing for transmitting movement from the shaft 35 to the shaft 313 is shown in Fig. 11 and comprises a partial gear 331 fastened to the shaft 35. The blank or locking portion 332 of the partial gear 331 is normally in engagement with one of three locking portions 333 of a gear 334 loose on a stud 330 fastened to the left hand frame 22. Rigid with the gear 334 is a slightly larger gear 335. The teeth of the gear 335 are at all times in mesh with a gear 336 fastened to the shaft 313.

When the shaft 35 is unlocked by withdrawal of the stop 54 from the path of the arm 55 and the shaft 35 rotated, the locking portion 332 of the partial gear 331 will simply ride idly in engagement with the locking portion 333 of the gear 334 until the shaft 35 has made about one-third of a rotation when an arm 341 rigid with the partial gear 331 will engage one of the three studs 342 attached to the gear 334 and start the gears 334 and 335 at the time that the teeth on the gear 331 come into engagement with the teeth on the gear 334. The gear 331 will then turn the gears 334 and 335 one-third of a rotation and drive the ticket feeding shaft 313. When the knife operating link 301 is drawn down to move the knife 277 forward to sever the ticket, the clutch pinion 323 will be disengaged from the gears 321 and 322. The cut-away portion 327 of the plate 283 is long enough to permit relative movement between the plate and the three armed member carrying the clutch pinion 323, the reason for this being that the entire movement of the plate 283 is not needed to engage and disengage the clutch pinion and its companion gears. A rod 343 serves to hold the pinions 323 in alignment when disengaged and the curved arm 328 performs a similar function for loose gear 321.

In order to make it possible to regulate the gripping action of the disks 311 and 314 the sleeves bearing the latter are mounted on the usual eccentrics 345 provided with setting clamps 346 by which the eccentrics may be adjusted to different positions and held in adjustment. Coöoperating with the clamps 346 are set screws 347 extending through shoulders 348 on the upper edge of the cross bar 24. The set screws 347 not only hold the clamps 346 and eccentrics 345 in position but they also afford a means by which an additional adjustment can be given the eccentrics without its being necessary to unloosen the clamps in case only a minor adjustment of the eccentrics is necessary.

Ticket counters.

The machine is provided with a counter 351 (Figs. 1 and 6) for each kind of tickets. When a key is depressed the corresponding counter will be connected to the driving mechanism and will remain connected as long as the key is held in depressed position, and as each ticket is issued the counter will be actuated to add one to the number previously shown thereon.

The mechanism for operating the counters is actuated by the rock shaft 116. This shaft, it will be remembered, is rocked once at each operation by the pitman 121 (Fig. 11). Fastened to the rock shaft 116 is a short arm 353 for each counter, to the upper ends of which arms are pivoted counter operating links 354. The counter operating links 354 are provided with bayonet slots 355 (Fig. 5) and surrounding studs 356 on the operating arms 357 for the counters. In the normal position of the keys studs 358 on the keys engage the undersides of the counter operating links 354 and hold them up in such position that when the shaft 116 is rocked the portions 359 of the bayonet slots 355 will be opposite the studs 356. When the machine is operated the link 354 of the undepressed key will, when it is thrust forward, have no effect on the corresponding counter. When the other key is depressed, however, the counter operating link 354 is free to drop to engage the nearly vertical portion of the bayonet slot 355 with the stud 356 and this movement is insured by a stud 365 on the key extending across the upper edge of the counter operating link 354. When the links 354 are thrust forward the one having the vertical portion of its slot engaged with the stud 356 will actuate its counter.

The studs 358 and 365, as shown in Figs. 5 and 6, are far enough apart to allow movement of the key arm 61 independently of the counter operating link 354. The purpose of this is to prevent the link 354 from being disengaged or otherwise disturbed when the key 61 is given the impulses previously mentioned by which the operator keeps count of the tickets as they are issued. It is apparent, however, that when the key 61 returns to its fully undepressed position, that is, when the arms 69 are allowed to drop, the studs 358 will raise the link 354 to the position shown thereby disconnecting the counter from the operating mechanism.

Operation.

In order to operate the machine to issue a single ticket of either kind the proper key 61 is simply depressed and the finger 130

immediately removed. This will cause the machine to be operated once and issue a single ticket. If more than one ticket is wanted, however, say ten tickets, the proper key is depressed and held depressed until ten tickets have been delivered. When the key is depressed it rocks the shaft 62 and raises the motor controlling arm 81 out of the path of the laterally extending flange 82 and the spring 99 will then immediately lift the motor controlling arm 53 out of engagement and serve through the connections 98, 97, 94, 93, 87 and 85 to rock the shaft 84 counter-clockwise (Figs. 6 and 10 8). Before this movement occurs, however, the key will have lifted the corresponding arm 69 to carry its stud 103 above the laterally extending flange 101 of the associated arm 102 fastened to the shaft so 15 20 that when the shaft is rocked the arm 69 will be latched in raised position. The arm 69 as it is moved to raised position will swing the printer connecting link 193 to engage its stud 196 with the slot 197 in 25 the operating arm 198 fastened to the rock shaft 199.

As soon as the driving mechanism begins its movement the shaft 199 is rocked to swing the impression rollers into feeding 30 position and carry the laterally extending flange of the arm 201 under the stud 202 on the arm 69. This movement of the shaft is effected by the link 211, bell crank 214 and pitman 215. When the motor controlling arm 53 was lifted by the spring 99 and the shaft 84 rocked, the link 93 swung the two armed connecting member 221 (Fig. 8) about its pivot 212 to carry the shorter arm of the member out of the path of the square 35 40 stud 225. As long as the key is held depressed the motor controlling arm 53 remains in its upper or ineffective position and the connecting member 221 is held with its arm out of the path of the stud 225 so 45 that the stud will clear the arm each time the link 211 is reciprocated. When the finger is removed from the key the arm 81 will drop into the path of the laterally projecting flange 82 so that when the member 50 55 60 65 70 75 80 85 90 95 100 105 110 115 120 125 130 89 is operated by its cam 111 the link 93 will be drawn forward to restore the motor controlling arm 53 and this will also return the connecting member 221 into position for its short arm to intercept the stud 225. Then when the link 211 makes its final movement the shaft 199 will be rocked back to its original position, thereby swinging the arm 201 to clear the stud 202 and allowing the arm 69 and printer connecting link 193 10 to be swung to their normal or ineffective position.

The time for removing the finger from the key to secure the number of tickets is indicated to the operator by the slight 65 70 75 80 85 90 95 100 105 110 115 120 125 130 pulse given to the key when the stud 118

(Fig. 6) engages the underside of the key 61 each time the shaft 116 is rocked. For example, if ten tickets are wanted the key is held down until the operator counts ten impulses, when he immediately removes his 70 finger from the key. This will give plenty of time for the arm 81 to drop down into position to intercept the laterally extending flange 82 on the arm 83 to disconnect the motor and stop the driving mechanism. 75

While the form of mechanism herein shown and described, is admirably adapted to fulfil the objects primarily stated, it is to be understood that it is not intended to confine the invention to the one form of 80 embodiment herein disclosed, for it is susceptible of embodiment in various forms all coming within the scope of the claims which follow.

What is claimed is:

1. In a machine of the class described, the combination of a ticket printing and issuing mechanism, means for operating said mechanism continuously to print any number of tickets desired, and a manipulative device controlling the number of tickets issued at an operation. 85

2. In a machine of the class described, the combination of a ticket printing and issuing mechanism, normally locked means 95 for operating said mechanism continuously to print and issue any number of tickets desired, and manipulative devices for releasing said means and stopping same when the desired number of tickets has been issued. 100

3. In a machine of the class described, the combination of a ticket printing and issuing mechanism, normally restrained means for operating said mechanism to 105 print and issue any number of tickets desired, and a key operable to release said means and stop same when the number of tickets desired has been issued.

4. In a machine of the class described, 110 the combination of a ticket printing and issuing mechanism constructed to run indefinitely to issue any number of tickets desired, a motor for driving said mechanism, the motor being normally disconnected 115 from the mechanism, and manipulative devices for connecting the motor and mechanism and disconnecting same after the number of tickets desired has been delivered.

5. In a machine of the class described, 120 the combination of a ticket printing and issuing mechanism, a motor for driving said mechanism to issue any number of tickets desired, devices operable to connect and disconnect said motor and the ticket mechanism, and a key controlling said devices. 125

6. In a machine of the class described, the combination of a ticket printing and issuing mechanism constructed to run indefinitely to issue any number of tickets desired, a 130

motor for driving said mechanism, the motor being normally disconnected from the mechanism, and a key operable to connect the motor and the mechanism and to disconnect same after the desired number of tickets has been delivered.

7. In a machine of the class described, the combination of a ticket printing and issuing mechanism constructed to issue any number 10 of tickets desired at an operation, said mechanism having a normal starting point, means for operating said mechanism continuously to print and issue any number of tickets desired, and a key operable to stop 15 the ticket printing mechanism at its normal starting point when the last ticket of a series has been issued.

8. In a machine of the class described, the combination of a ticket printing and issuing 20 mechanism constructed to issue any desired number of tickets at an operation, a manipulative device for controlling the number of tickets issued at an operation, and means for imparting a counting impulse to 25 the manipulative device as each ticket is printed.

9. In a machine of the class described, the combination of a ticket printing and issuing mechanism constructed to deliver any desired 30 number of tickets at an operation, a manually operated key for controlling the number of tickets issued at an operation, and means for imparting a counting impulse to the key as each ticket is printed and 35 issued.

10. In a machine of the class described, the combination of a plurality of independent ticket printing and issuing mechanisms, an operating mechanism common 40 thereto, manipulative devices operable to connect the desired ticket printing and issuing mechanism to said operating mechanism, and means for imparting a counting impulse to the operated manipulative 45 device as each ticket is issued.

11. In a machine of the class described, the combination of a plurality of ticket printing and issuing mechanisms, an operating mechanism common thereto, a plurality 50 of keys selectively operable to connect the desired ticket printing and issuing mechanism and the common operating mechanism, and means for imparting a counting impulse to the operated key as 55 each ticket is issued.

12. In a machine of the class described, the combination of a plurality of ticket printing and issuing mechanisms, an operating mechanism common thereto, keys 60 operable singly or in unison to couple one or more of the ticket printing and issuing mechanisms to the common driving mechanism, and means for imparting counting impulses to the operated keys as the tickets 65 are issued.

13. In a machine of the class described, the combination of a plurality of ticket printing and issuing mechanisms, an operating mechanism common thereto, manipulative devices selectively operable to 70 connect one of the ticket printing and issuing mechanisms to the common driving mechanism and maintain the connection until any number of tickets desired have been delivered, and means controlled by the manipulative devices for rendering the effective ticket printing and issuing mechanism 75 ineffective as the last ticket is issued.

14. In a machine of the class described, the combination of a plurality of ticket 80 printing and issuing mechanisms, an operating mechanism common thereto, manipulative devices selectively operable to connect one of the ticket printing and issuing mechanisms to the common driving 85 mechanism and maintain the connection until any number of tickets desired have been delivered, means controlled by the manipulative devices for rendering the effective ticket printing and issuing mechanism 90 ineffective as the last ticket is issued, and means for imparting counting impulses to the manipulative device.

15. In a machine of the class described, the combination of a plurality of ticket 95 printing and issuing mechanisms, an operating mechanism common thereto, keys selectively operable to connect one of the ticket printing and issuing mechanisms to the common driving mechanism and maintain the connection until any number of tickets desired have been delivered, and means controlled by the keys for rendering the effective ticket printing and issuing mechanism 100 ineffective as the last ticket is issued.

16. In a machine of the class described, the combination of a plurality of ticket printing and issuing mechanisms, an operating mechanism common thereto, keys 110 selectively operable to connect one of the ticket printing and issuing mechanisms to the common driving mechanism and maintain the connection until any number of tickets desired have been delivered, means 115 controlled by the keys for rendering the effective ticket printing and issuing mechanism ineffective as the last ticket is issued, and means for imparting counting impulses to the manipulative device.

17. In a machine of the class described, the combination of a plurality of ticket printing and issuing mechanisms, a shaft common thereto, means for rotating said shaft any desired number of times according to the number of tickets desired, manipulative devices, and means controlled by said manipulative devices for selectively connecting the ticket mechanisms to the shaft.

18. In a machine of the class described, the combination of a plurality of ticket printing and issuing mechanisms, a shaft common thereto, means for rotating said shaft any desired number of times according to the number of tickets desired, manipulative devices, means controlled by said manipulative devices for selectively connecting the ticket mechanisms to the shaft, and means for imparting a counting impulse to the manipulative devices at each rotation of the shaft.

19. In a machine of the class described, the combination of a ticket mechanism comprising a rotating cylinder, devices carried by the cylinder for printing and feeding a ticket from a ticket strip at each rotation of the cylinder, an impression roller for holding the strip in feeding and printing contact with the cylinder, said roller being normally out of effective relation with the cylinder, manipulative devices, and means controlled by the manipulative devices for holding the impression roller in effective relation during any desired number of rotations of the cylinder.

20. In a machine of the class described, the combination of a ticket mechanism comprising a rotating cylinder, devices carried by the cylinder for printing and feeding a ticket from a ticket strip at each rotation of the cylinder, an impression roller for holding the strip in feeding and printing contact with the cylinder, said roller being normally out of effective relation with the cylinder, and a key for holding said roller in effective position during any desired number of rotations of the cylinder.

21. In a machine of the class described, the combination of a ticket printing and issuing mechanism, an operating mechanism therefor, a lock normally preventing operation of the operating mechanism, a manipulative device operable to disable said lock and return same to effective condition at the end of any ticket issuing operation, and means for imparting a counting impulse to the manipulative device.

22. In a machine of the class described, the combination of a ticket printing and issuing mechanism, an operating mechanism therefor, a lock normally preventing operation of the operating mechanism, a key operable to disable said lock and return same to effective condition at the end of any ticket issuing operation, and means for imparting a counting impulse to the key.

23. In a machine of the class described, the combination of a plurality of ticket printing and issuing mechanisms, an operating mechanism common thereto, an accounting device for each ticket mechanism,

and means for connecting any desired one of the mechanisms and its accounting device to the operating mechanism and disconnecting same after any number of tickets desired have been issued.

24. In a machine of the class described, the combination of a ticket printing and issuing mechanism, normally restrained means for operating said mechanism to print and issue any number of tickets desired, and a key operable to release said means by a movement in one direction and to stop same when the number of tickets desired has been issued by movement in the opposite direction.

25. In a machine of the class described, the combination of a ticket printing and issuing mechanism, actuating mechanism therefor, manipulative means for connecting and disconnecting the same, means for moving the same for printing a single ticket, means for indicating upon said manipulative means that a single ticket has been printed, means for moving said manipulative means after said indication and disconnecting the ticket printing and issuing mechanism from its actuating mechanism.

26. In a machine of the class described, the combination of a ticket printing and issuing mechanism, an operating mechanism therefor, a lock normally preventing operation of the actuating mechanism, a key operable to disable said lock and return same to effective condition at the end of any ticket issuing operation, said key serving to initiate actuation of said device and to determine the number of tickets issued.

27. In a ticket machine, ticket printing and issuing mechanisms, actuating means therefor, manipulative means for connecting the foregoing, means for indicating the number of tickets by means of physical contact with the operator near the end of the issuance of the desired series.

28. In a machine of the class described, the combination of a ticket printing and issuing mechanism, an actuating mechanism therefor, manipulative means therefor joining the foregoing, an impulse means operating thereon and indicating each ticket as printed whereby the length of series of tickets can be determined at the time of printing.

29. In a machine of the class described, the combination of a ticket printing and issuing mechanism, an operating mechanism therefor, means for restraining the action of said mechanism, means for removing said restraint, and means for returning it at will after the printing of any ticket in any desired length series.

30. In a machine of the class described,

the combination of a ticket printing and issuing mechanism, an operating mechanism therefor, manipulative means for connecting the foregoing mechanisms, and indicator means acting thereon and showing the printing of each ticket, and means for disconnecting the ticket printing and issuing mechanism and operating mechanism and thus determining the number of tickets issued just prior to the issuance of 10 the last ticket.

In testimony whereof I affix my signature.

HAAKON A. MARTIN.
